GAME BOARD HAVING CHANGEABLE PATTERN
Kenneth S. Caplan, 471 Park Ave., Elmhurst, Ill.
Filed May 16, 1962, Ser. No. 195,296
9 Claims. (Cl. 273—136)

This invention relates to a game and to a novel game board which forms a part thereof.

It is an object of the present invention to provide a game having a game board formed by a plurality of relatively movable sections that form a pattern over which the game is played and wherein one or more of the sections may be shifted relative to the other to vary the pattern as the game is being played. In accordance with the preferred embodiment of the present invention, the game board has a plurality of parallel adjacent strips. Each strip has a single line of alternately colored squares and extends across the board, and the strips may be positioned relative to each other to form a conventional checkerboard pattern. Each strip is, furthermore, independently slideable longitudinally an amount equal to the width of one square, whereby to vary the checkerboard pattern as by forming a plurality of rectangular rows of squares of the same color. The number of similarly colored squares in each row will depend upon the number of strips that have been shifted.

It is also an object of the present invention to provide a game having a game board of the type stated in which the variable playing pattern is overlaid by a transparent member that remains stationary when the strips are shifted to change the pattern. The transparent member constitutes a playing area over which a plurality of checkers or other disconnected objects are movable in relation to the subjacent pattern, in accordance with the rules of the game. The transparent member supports the objects whereby they remain stationary when the slideable strips are shifted to change the game board pattern.

It is also an object of the present invention to provide a game of the type stated which is interesting and entertaining, and which is relatively inexpensive to construct.

The attainment of the above and further objects of the present invention will be apparent from the following specification taken in conjunction with the accompanying drawing forming a part thereof.

In the drawing:

FIG. 1 is a perspective view of a game constructed in accordance with and embodying the present invention;

FIGS. 2 and 3 are sectional views taken along lines 2—2 and 3—3 respectively of FIG. 1; and

FIG. 4 is a perspective view similar to FIG. 1 and showing the play of the game.

Referring now in more detail and by reference characters to the drawing, which illustrates a preferred embodiment of the present invention, A designates a game comprising a game board 1. The game board 1 includes a jacket 3 having top and bottom rectangular cardboard plies 5, 7, the top ply 5 having a large square opening 9 therein that leaves a border 10 on the ply 5. The plies 5, 7 are permanently secured together at their margins by binding tapes 11, 13, 15, 17.

Mounted for longitudinal sliding movement between the plies 5, 7 are eight adjacent parallel cardboard strips 19, 21, 23, 25, 27, 29, 31, 33, the upper surfaces of which are approximately coplanar. Each strip carries on its upper surface a single line of nine squares 35a, 35b, eight of which are normally visible through the opening 9. The squares 35a are of a different color than the squares 35b and are alternately arranged along each strip. Furthermore, similarly colored squares in one strip are in opposite alternate arrangement with those of the adjacent strip.

2

Thus, when the strips are in the position shown in FIG. 1, the pattern exposed through the opening 9 will be a standard sixty four square checkerboard.

The endmost squares of each strip may actually be 5 slightly elongated as at end portions 37, 39 and hence not truly square. However, since the elongated portions 37, 39 underlie the opaque top ply 5, the exposed parts of those squares appear substantially square-shaped.

Riveted or otherwise rigidly secured to the strips 19, 10 21, 23, 25, 27, 29, 31, 33 at their end portions 37 are knobs 41, 43, 45, 47, 49, 51, 53, 55 that project through parallel slots 57, 59, 61, 63, 65, 67, 69, 71 in the border 10 of the top ply 5. The knob on each ply may be grasped to shift that strip longitudinally independently of the 15 other strips, the amount of shifting being limited by the abutment of the knobs at the end of the slots 57, 59, 61, 63, 65, 67, 69 and 71. The slots are each of a length such that each strip is able to move longitudinally an amount equal to the width of one square.

20 A transparent, substantially form-sustaining plastic sheet 73 is used to cover the checkerboard pattern. The sheet 73 is square and has a marginal flange 75 extending completely therearound and tucked under the border 10 to retain the sheet 73 in place. The central portion 77 25 of the sheet 73 may be raised above the strips 19, 21, 23, 25, 27, 29, 31, 33.

Two groups of checkers or other disconnected objects B and R may be shifted about, in accordance with the rules of the game, over the playing area constituted by 30 the surface of the transparent sheet 73. Any of the knobs 57, 59, 61, 63, 65, 67, 69, 71 may be grasped to shift the associated strip an amount equal to the width of one of the squares of the checkerboard without moving the checkers B and R from their positions. If all of the strips 35 are in their initial position (FIG. 1) and one of the strips, for example strip 31, is shifted, as shown in FIG. 4, the pattern on the checkerboard is changed and a plurality of rows of squares of the same color are produced. Those 40 rows will be formed from the strips 29, 31, 33 and each row will have three consecutive light squares 35a or dark squares 35b, as the case may be. Other changes in the pattern of the squares may be made by shifting others of the strips back and forth and various combinations of shifted strips will produce various patterns.

45 In playing one type of game that uses the game board of the present invention, two players place their respective checkers B, R on the strips 19, 33, as shown in FIG. 1, all of the strips being in their initial positions so that a checkerboard pattern is formed.

50 The player having checkers R tries to get as many as possible of those checkers onto the squares (35a or 35b) in the strip 19 while the player with the checkers B tries to get as many as possible of his checkers onto the squares in the strip 33. The player who has the most checkers in the last row (strips 19 or 33) of his opponent's field and cannot make another move or play wins the game.

Each player must shift one of the strips before each 55 checker move, and each player can shift only one of the strips in his own playing field, except under conditions hereinafter explained. For example, the player with the checkers R can shift only the strips 27, 29, 31, 33. After shifting one of the strips the player may move his checker only along certain paths. He may move forward along all dark squares 35b to the last dark square in the line of squares, or on a diagonal left or right on all light squares 35a to the last light square in the diagonal line. Also, when a checker is on a light square 35a it may be moved to the right or left to the adjacent dark square 35b of that strip. Each player also tries to remove the opponent's checkers from the game by "capturing" them. This is done when an opponent's

checker lies in the path of the checker being moved.

In FIG. 4 typical first moves of the players are shown. The player with checkers R has shifted the strip 31 and moved one of his checkers along a row of dark squares 35b from the dotted to the full line positions. The player with checkers B shifts the strip 25 and moves diagonally along a row of light squares 35a.

Further shifts of the strips and moves by the players are made successively, advancing the checkers and "capturing" opponent's checkers. Checkers once "captured" are not returned to the game. When one checker of either player has penetrated into the opponent's field, namely, onto one of the four strips theretofore shiftable only by that opponent, the player who has succeeded in making the penetration is no longer limited to shifting the strips on his own field but may now shift any one of the strips of the board before moving. Depending upon the play the same strip may be shifted back and/or forth a number of times by both players.

Checkers that a player finally succeeds in getting into the opponent's last row are "scored" and these checkers cannot be moved again or "captured" by an opponent. The underlying strip may, however, be shifted. When a player has all of this remaining checkers in the last row of the opponent's field the game is over and the winner is the one having the greatest number of checkers in the opponent's last row.

Other games and variations of the game just described may be played with the game board and objects B, R. Furthermore, while a standard sixty four square checkerboard formed by eight strips is illustrated, other sizes of checkerboards are within the scope of the present invention. For example, the one hundred square so-called Polish checkerboard may be used in which case the strips will each have ten squares exposed to view and each player will have ten checkers.

In compliance with the requirements of the patent statutes I have herein shown and described a preferred embodiment of the invention. It is, however, to be understood that the invention is not limited to the precise construction herein shown, the same being merely illustrative of the principles of the invention. What is considered new and sought to be secured by Letters Patent is:

1. A game board having a plurality of plies one of which has an opening, a plurality of parallel relatively slideable adjacent strips slideable between the plies, the surfaces of the strips having a plurality of alternately colored squares disposed in a checkerboard pattern exposed through said opening, each strip carrying a single line of alternately colored squares and extending across and beyond the pattern region, each strip furthermore being independently slideable longitudinally an amount equal to the width of one square, means for limiting the amount of shifting movement of each strip to the amount specified, said means comprising a plurality of slots in the ply having the opening, each slot being parallel to one of the strips and of a length equal to the width of one square, and a knob on each strip projecting through one slot for manipulating the strip, and a transparent member overlying the pattern at said opening and remaining stationary upon sliding of any of said strips.

2. A game board comprising a jacket having an opening therein, a transparent sheet covering the opening, means in the jacket forming a game board pattern that underlies the transparent sheet and is exposed to view therethrough, said means comprising a plurality of slideable strips each of which carries a portion of the pattern, and means for shifting each strip independently of the transparent sheet and of the other strips to change the pattern.

3. A game board comprising a region having a plurality of members each having a pattern and together forming a predetermined game board pattern, a transparent member covering the pattern and forming a playing surface, and means for shifting one of the members rela-

tive to the other to change the game board pattern without moving the transparent member.

4. A game board comprising a plurality of plies one of which has an opening, a plurality of relatively shiftable members the corresponding surfaces of which constitute a surface having alternately colored squares in a checkerboard pattern, said members being shiftable between the plies with the squares being exposed through said opening means for shifting the members an amount sufficient to change the pattern of the squares on the surface to form rectangular rows of squares of the same color, and a transparent member overlying the shiftable members at said opening and remaining stationary upon shifting of the members.

5. A game comprising a game board having a plurality of plies one of which has a square opening, a plurality of relatively shiftable strips between the plies, the corresponding surfaces of which constitute alternately colored squares forming a checkerboard pattern, said strips exposing the pattern through the opening means for shifting the strips independently an amount sufficient to change the pattern of the squares to form rectangular rows of squares of the same color, a transparent member overlying the strips and forming a playing surface, and a plurality of disconnected objects on the playing surface for movement thereon in relation to the squares and remaining stationary upon shifting of the strips.

6. A game comprising a game board having an area of alternately colored squares in a checkerboard pattern, a transparent member covering said area and forming a playing surface, a plurality of disconnected objects supported by the transparent member for movement thereon, and means for changing the pattern of the squares to form at least one rectangular row of squares of the same color without moving the objects on the transparent member; said means including selectively shiftable area sections, and means for limiting the movement of each section to an amount equal to the width of the squares.

7. A game comprising a game board having a jacket with an opening, a plurality of parallel adjacent strips, the strips being relatively slideable within the jacket, the corresponding surfaces of the strips being substantially coplanar, each strip having a single line of alternately colored equally sized squares, the squares on all of the strips together forming a checkerboard pattern exposed through said opening, a transparent sheet covering the opening, a plurality of disconnected objects supported by the transparent member for movement thereon, means associated with each strip for sliding any one of the strips longitudinally and independently of the others an amount equal to the width of one square without moving the objects on the transparent member, and means for limiting the amount of sliding movement of each strip to the amount specified, whereby to change the checkerboard pattern by forming a plurality of rectangular rows of squares of the same color.

8. A game comprising a game board having a jacket with top and bottom plies marginally secured together, said top ply having a large opening therein, a plurality of parallel adjacent strips, the strips being relatively slideable independently of each other between the plies, the corresponding surfaces of the strips being substantially coplanar, each strip having a single line of alternately colored equally sized squares, the squares on all of the strips together forming a checkerboard pattern exposed through said opening, a transparent form-sustaining sheet across said opening, said top ply having a plurality of parallel slots equal in number to the number of said strips, each slot being of a length equal to the width of a square, knobs secured to the strips and projecting upwardly through the slots for moving any of the strips independently of the other, the abutment of the knobs at the ends of the slots limiting the movement of the strips by an amount equal to the width of one square, whereby to change the checkerboard pattern by forming a plurality of rectangular rows of squares of the same color.

9. A game comprising a game board having a jacket having top and bottom plies marginally secured together, said top ply having a large square opening therein that leaves a border immediately adjacent to said opening, a plurality of parallel adjacent strips, the strips being relatively slidable independently of each other between the plies, the corresponding surfaces of the strips being substantially coplanar, each strip having a single line of alternately colored equally sized squares, the squares on all of the strips together forming a checkerboard pattern exposed through said opening, a transparent form-sustaining sheet across said opening, said sheet having a margin that fits under said border to support the central part of the sheet in a plane upwardly from the plane of the top ply, a plurality of disconnected objects supported by the transparent sheet for movement thereon, said border having a plurality of parallel slots equal in num-

ber to the number of said strips, and being perpendicular to two opposite edges of the border, each slot being of a length equal to the width of a square, knobs secured to the strips and projecting upwardly through the slots for moving any of the strips without moving the objects on the transparent sheet, the abutment of the knobs at the ends of the slots limiting the movement of the strips by an amount equal to the width of one square, whereby to change the checkerboard pattern by forming a plurality of rectangular rows of squares of the same color.
